UNITED STATES PATENT OFFICE.

JOSEPH MESSINA, OF BENLD, ILLINOIS.

STOVEPIPE.

1,209,008.

Specification of Letters Patent. Patented Dec. 19, 1916.

Application filed June 30, 1916. Serial No. 106,907.

To all whom it may concern:

Be it known that I, JOSEPH MESSINA, a citizen of the United States, residing at Benld, in the county of Macoupin and State of Illinois, have invented new and useful Improvements in Stovepipes, of which the following is a specification.

This invention relates to a stove pipe and more particularly to a stove pipe in which the pipe sections from which the stove pipe is formed are so constructed and arranged with relation to each other as to render the stove pipe extensible.

The primary object of the invention is to provide a stove pipe of this character wherein a sleeve engaged with one of said sections is movable longitudinally of the other pipe section and provided at one end with a spring finger engageable with depressions in the pipe section on which the sleeve is movable to hold the sleeve in adjusted position thereon.

Another object of the invention is to provide the pipe section upon which the sleeve is movable with a circumferentially extending groove arranged near the end of the pipe section which is received within the sleeve and which when brought into engagement with the spring finger on the sleeve prevents said pipe section from being withdrawn from within the sleeve during the adjustment of the same.

A further object of the invention is to provide the sleeve which connects the pipe sections with an inturned portion at one end thereof which provides the sleeve with an internal collar which snugly encircles the pipe section upon which the sleeve is adjustable and prevents the escape of smoke from between the sleeve and pipe section irrespective of the position of the sleeve upon said section.

A still further object of the invention is to provide the sleeve which is adjustable upon one of the pipe sections with an inturned flange which when brought into contact with a circumferentially extending bead on the other pipe section serves to support said pipe section and limit the extent to which an end on said section may extend within said sleeve.

With these and other objects in view, the invention resides in the novel combination and arrangement of parts, which will be hereinafter described and particularly pointed out in the claims.

The preferred embodiment of the invention has been illustrated in the accompanying drawing, although no restriction is necessarily made to the precise details of construction therein shown, as changes, alterations, and modifications, within the scope of the claims may be resorted to when desired.

Like characters of reference denote corresponding parts throughout the several views in the drawing, in which:

Figure 1 is a view in elevation of a stove pipe constructed in accordance with the invention and showing the same in extended position. Fig. 2 is a view similar to Fig. 1 showing the sleeve and pipe sections partly in section. Fig. 3 is a view in elevation of the stove pipe showing the same in retracted position. Fig. 4 is a view similar to Fig. 3 showing the sleeve and pipe sections partly in section.

Referring now to the drawing in detail, the numeral 1 designates the improved stove pipe which comprises pipe sections 2 and 3 connected through the medium of a sleeve 4 into which each pipe section extends for a portion of its length, said sleeve 4 being movable longitudinally of the pipe section 2 to render the stove pipe extensible and to allow an end 5 on the pipe section 2 to be brought into contact with an end 6 on the pipe section 3 when the stove pipe is in normal position. Each of the pipe sections 2 and 3 has formed thereon near its free end a circumferentially extending bead 7 which enables a smoke tight joint to be formed when said sections are connected with elbows, pipe sections, or the like.

The sleeve 4 has formed thereon at the end in which the end 6 of the pipe section 3 is received an inturned flange 8 contacting with a circumferentially extending bead 9 on the pipe section 3, said flange and bead limiting the extent to which the end 6 of the pipe section 3 may extend within said sleeve and also providing a support for said section which enables the pipe section 3 to be moved when the sleeve 4 is moved longitudinally of the pipe section 2. The other end of the sleeve 4 through which passes the pipe section 2 has an inturned portion forming a collar 10 within the sleeve, said collar snugly encircling the pipe section 2 and serving to prevent the escape of smoke between the sleeve 4 and pipe section 2 irrespective of the position of the sleeve 4 upon said pipe section. The sleeve 4 has formed therein a pair

- of spaced slits 11 extending longitudinally of the sleeve 4 the entire length of the collar 10 to enable the portion of the sleeve which is arranged between the slits to provide a spring finger 12 which extends beyond the slotted end of the sleeve and is provided with a transversely extending groove forming upon the finger 12 a locking rib 13 terminating in an out-turned releasing lip 14.
- 10 The pipe section 2 is provided on its outer peripheral surface between the bead 7 and end 5 which is received in the sleeve 4 with a longitudinally extending row of spaced depressions 15 arranged in the path of movement of the locking rib on the spring finger 12 so that as the sleeve 4 is moved longitudinally of the pipe section 2, the locking rib may be received in the depressions 15 to hold the sleeve 4 in adjusted position upon the pipe section 2. The pipe section 2 is further provided near the end 5 on its outer peripheral surface with a circumferentially extending groove 16 which when brought into contact with the locking rib on the spring finger 12 prevents the accidental removal of the pipe section 2 from within the sleeve irrespective of the position of the spring finger with relation to the depressions 15 in the pipe section 2.
- 20 When it is desired to connect the improved stove pipe with a stove and chimney, the sleeve 4 is moved to its normal or retracted position upon the pipe section 2 and the pipe section 2 connected with a stove or the like.
- 30 The pipe section 3 is now connected with a chimney through the medium of an elbow, or the like; and the locking rib 13 removed from the lowermost notch in the pipe section 2 by pressure upon the releasing lip 14.
- 40 The sleeve 4 may now be moved longitudinally of the pipe section 2 until the end 6 of the pipe section 3 is received within the sleeve 4 at which time the spring finger may be released to enable the locking rib thereon to engage with a depression 15 in the pipe section 2, thus holding the sleeve in adjusted position upon the pipe section 2 and the stove pipe in extended position.

Through the above described manner of connecting the sleeve with the pipe sections, it will be seen that the parts of the stove pipe may be easily disconnected for cleaning purposes when desired and that through the provision of the flange 8 on the sleeve 4

a smoke tight joint between the pipe section 3 and sleeve 4 is provided if the bead 9 is not in contact with the flange 8.

From the foregoing statements, taken in connection with the accompanying drawing, it is at once apparent that a stove pipe has been provided which is so constructed as to render the same extensible and through its simple construction is inexpensive of manufacture, although highly efficient in use.

Having thus described the invention, what is claimed as new, is:

1. A stove pipe comprising a pipe section, a sleeve movable longitudinally thereof, an inturned portion on said sleeve providing an internal collar on the sleeve for contact with the pipe section, means on the pipe section and sleeve co-acting to lock the sleeve against longitudinal movement on the pipe section, an inturned flange on said sleeve, and a second pipe section having an end extended within the sleeve and bearing against said flange.

2. A stove pipe comprising a pipe section having a longitudinally extending row of spaced depressions in its outer peripheral surface, a sleeve movable longitudinally of the pipe section, an inturned portion at one end of the sleeve providing an internal collar engaging said pipe section, a spring finger on the sleeve extending beyond the collar to engage with said depressions as the sleeve is moved longitudinally of the pipe section, and a second pipe section removably connected with the other end of the sleeve.

3. A stove pipe comprising a sleeve slotted for a portion of its length to provide a finger having a depression therein providing a locking rib, a pipe section connected with one end of the sleeve, a second pipe section extending within the sleeve for a portion of its length and having a longitudinally extending row of spaced depressions to receive the locking rib on the finger when the sleeve is moved longitudinally of the second mentioned pipe section, and an internal bead on the second mentioned pipe section providing an external and circumferentially extending groove thereon arranged in the path of movement of the finger to receive said locking rib.

105 In testimony whereof I affix my signature.

JOSEPH MESSINA.
